RAYMOND N. EHRHART, OF EDGEWOOD, PENNSYLVANIA, ASSIGNOR TO ELLIOTT COMPANY, OF PITTSBURGH, PENNSYLVANIA, A CORPORATION OF PENNSYLVANIA

CONDENSER

Application filed February 11, 1926. Serial No. 37,545.

The present invention relates broadly to the art of heat exchangers and method of operating the same, and more particularly to surface condensers.

5 It has heretofore been proposed in the art to which the present invention relates to provide surface condensers with cells or compartments of different condensing capacities. The control of such condensers has, however, 10 presented a very considerable problem. In some cases there have been provided valves to apportion the steam to the various cells in accordance with their condensing capacities. When it is considered that the exhaust 15 opening of a 30,000 kw. turbine, for example, is approximately 8 feet by 16 feet, it will be readily apparent that since each valve must be of a size to handle in the neighborhood of one third of the steam exhausted, the 20 valves are of such magnitude as to make them not only extremely cumbersome and difficult to mount and operate, but also very expensive. Controlling valves of this general character, have, therefore, not gone into any 25 extended use.

In other cases engineers in the art have attempted to solve the problem by the use of separate air pumping means for each of the cells or compartments of the condenser, the 30 air pumps each being of such size that the full capacity of each compartment could be obtained. The use of a multiplicity of air pumping means, however, introduces complications both from a manufacturing and 35 operating standpoint, together with additional cost, all of which are objectionable.

It has also been proposed to utilize but one air pump and provide the same with separate regulating valves to the individual compartments. To those skilled in the art it is well understood that widely different operating 40 conditions are encountered with a given installation, and such conditions frequently necessitate manual operation of the individual valves. This is not desirable, as it requires not only a skilled operator at all times, but careful adjustment of the individual 45 valves in order to insure proper results.

The present invention has for one of its 50 objects the simplification of condensers of the

general character referred to both with respect to construction and operation, by the elimination of steam distributing valves, separate air pumping means, separate air off-takes or regulating valves, or similar means, with the elimination of their inherent objections.

55 In the accompanying drawings there is shown for purposes of illustration only, a preferred embodiment of the present invention, it being understood that the drawings do not define the limits of my invention and changes in the construction and operation 60 therein disclosed may be made without departing either from the spirit of the invention 65 or the scope of my broader claims.

In the drawings:

Figure 1 is a longitudinal sectional view, largely diagrammatic, through one form of 70 condenser embodying the present invention, and

75 Figure 2 is a partial transverse sectional view on the line II-II of Figure 1 looking in the direction of the arrows.

In a multi-cellular condenser in which the 80 cooling or condensing water makes but a single pass through the tubes, and therefore usually referred to as a single pass condenser, a cell or compartment of given size nearest the cold end of the condenser, the end first 85 receiving the cooling water, has obviously a greater condensing capacity than a similar cell or compartment more remote from the cold end of the condenser, the capacity being least adjacent the end of the condenser from 90 which the cooling water is discharged. If each of the cells condenses to its full capacity, the one condensing the most steam will 95 obviously have the greatest pressure loss measured at the extremes of the steam flow zone. It necessarily follows that as the pressure of the steam at the inlet of all of the cells is substantially the same, the pressures at the termini of the respective cells must be different. It is for this reason that it has heretofore been considered necessary to have either separate air pumping means to separately handle the non-condensable gases or 100 to have valve means adjustably connecting the individual cells to a single air pumping

means. If, however, large valves with their attendant objections, as referred to, are placed at the steam inlet to the respective cells, the loss of pressure can be equalized for all of the cells by proper setting of the valves, thereby permitting a single air pumping means to be utilized. My invention contemplates similar results without the use of any valves.

Where a single air offtake is used on single pass condensers as heretofore designed, any increased air pumping capacity has withdrawn an increased amount of vapor from any cell which is doing its full quota of condensing work. If certain cells are doing their full quota of work, and other cells are not, it is impossible to increase the overall condensing capacity of such other cells by increasing the capacity of the air pumping means, as such means will simply draw an excess amount of vapor from such cell or cells as are already doing their full quota. In accordance with the present invention, I prevent such excess vapor withdrawal from any cell or cells, for example, by providing an opening of limited area in the gas offtake of the compartment.

In carrying out the present invention there may be provided a condenser comprising a water header 2 having a suitable water inlet 3, and a similar header 4 having a water outlet 5, these headers being connected by tubes 6 as is customary in the art. The tubes and headers are of such construction that a single pass for the cooling or condensing water is provided.

The interior of the condenser may be divided into any number of cells, as indicated by the reference characters 7, 8 and 9, by suitable baffles 10 and 11 disposed as desired. These cells respectively have steam or vapor inlets 12, 13 and 14 all communicating with the main vapor intake 15 of the condenser, and providing a vapor flow through the cells in parallel, while the water flow is in series therethrough.

The partition 10 is provided with an opening 16 constituting an outlet from the cell 7 into the cooler cell 8 for vapors and non-condensable gases, while 17 is a similar opening through partition 11 from cell 8 into the still cooler cell 9. An offtake 18 is in turn provided for communication with any suitable pumping or exhausting means capable of handling the amounts of gas and vapor incident to condenser operation.

With the construction shown it will be seen that all gases and vapors leaving the warmest cell 7 must travel through all of the other cells, the direction of gas and vapor flow from cell to cell being counter to the direction of water flow. The openings 16 and 17 permitting this travel are preferably located beneath a baffle 19 herein illustrated as being generally of inverted V-shape. The gases

and vapors flow in cell 7 into the space below the baffle, and thence through opening 16 into the next cell. Beneath the baffle in cell 8 there are preferably provided baffles or other flow obstructing means 20, whereby fluid entering through the opening 16 is deflected and caused to flow through at least a portion of the tube zone of the cell 8. The underside of the baffle in cell 9 is similarly provided with baffles 21 for correspondingly producing a fluid flow from opening 17 into at least a portion of the tube zone of the cell 9. The openings 16, 17 and 18 are graded in size as each in succession must handle an increased amount of gas and vapor.

In operation, with a construction of the character herein contemplated, cooling water entering at 3 and leaving at 5 traverses the tubes 6 with the result that condensation occurs in all of the cells. The condensation in cell 9 heats the cooling water to some extent, so that there is less condensation in cell 8, and correspondingly less in cell 7 due to additional heat imparted in cell 8. As there is a less vapor flow through cell 8 than through cell 9 there will be a greater pressure loss through cell 9 than through cell 8, and the pressure at the terminus of cell 9 will be less than at the terminus of cell 8, and, likewise the pressure at the terminus of cell 8 will be less than at the terminus of cell 7.

In general, I have found it to be desirable to grade the area of the openings 16, 17 and 18 in proportion to the amount of fluid each must handle. If, for example, the condensing capacity of cells 7, 8 and 9 is in the ratio of 400, 500 and 600, then the openings might conveniently be proportioned as follows:

Area 16 proportioned to 400.

Area 17 proportioned to 400 plus 500.

Area 18 proportioned to 400 plus 500 plus 600.

Furthermore, the areas for these openings are preferably such that there will be a pressure drop of, say, a few hundredths of an inch of mercury through them when passing about triple the normal air with its accompanying vapor. When each of the cells is working up to its normal condensing capacity it discharges roughly two pounds of vapor with every pound of air through its terminus or outlet, either into the next cell as in the case of cells 7 and 8 or directly to the air pumping means as in the case of cell 9. If more steam enters a cell such as 7, than can be condensed therein, the pressure at the terminus of such cell will rise, since the opening 16 is so small that the steam cannot be withdrawn rapidly enough to keep the pressure down.

The obstructions or baffles 21 operate to prevent overloading of the pumping means by an excess of vapor from incomplete condensation in cells 7 and 8, by deflecting such vapor into the tube space of the next cell

where it is condensed. Normally there should be the lowest pressure at the terminus of cell 9, and my present condenser admirably accomplishes this inasmuch as cell 9 is in direct communication with the pumping means. Also, the natural loss of pressure through the openings 16 and 17 likewise tends to grade the pressure as desired.

The condensate from the condenser may be removed through branch conduits leading from a main conduit 22. On account of the different pressure obtaining at the termini of the respective cells, it will be apparent that the condensate will stand at different levels in the branches as indicated in Figure 1. Any suitable means, such as a centrifugal pump 23, may be used to finally exhaust the condensate and deliver it to the desired point.

The advantages of the present invention arise from the provision of a multi-cellular single pass condenser in which the terminal fluid flow from each of the cells is definitely restricted.

Further advantages arise from the provision of a multi-cellular condenser of the character referred to in which cumbersome or manually operable valves are obviated, and in which it is possible to obtain both the desired pressures at the termini of the respective cells, and the desired gas and vapor offtake by the use of a single exhausting means.

Still further advantages arise from the provision of means in a condenser of the character herein contemplated operable to prevent an excess of vapor in certain of the cells from overloading the exhausting means.

I claim:

1. In a single pass surface condenser, means providing a plurality of cells having a vapor flow therethrough in parallel and a water flow therethrough in series, and means for directing a flow of gas from the terminus of at least one cell later to receive cooling water into a cell earlier to receive cooling water.

2. In a single pass surface condenser having cooling tubes, means providing a plurality of cells having a vapor flow therethrough in parallel and a water flow therethrough in series, and means for directing a flow of gas from the terminus of at least one cell later to receive cooling water into a cell earlier to receive cooling water and through the tube zone therein.

3. In a single pass surface condenser, means providing a plurality of cells having a vapor flow therethrough in parallel and a water flow therethrough in series, and means for directing a flow of gas from the termini of the cells later to receive cooling water successively into the cells earlier to receive cooling water.

4. In a single pass surface condenser, means providing a plurality of cells having

a vapor flow therethrough in parallel and a water flow therethrough in series, and means for directing a flow of gas from the terminus of at least one cell later to receive cooling water into a cell earlier to receive cooling water, said cell earlier to receive cooling water having means therein to insure cooling of the gas directed thereto.

5. In a single pass surface condenser, means providing a plurality of cells having a vapor flow therethrough in parallel and a water flow therethrough in series, and means for directing a flow of gas from the terminus of at least one cell later to receive cooling water into cells earlier to receive cooling water, said cells earlier to receive cooling water having means therein to insure cooling of the gas directed thereto.

6. In a single pass surface condenser, means providing a plurality of cells having a vapor flow therethrough in parallel and a water flow therethrough in series, and means for directing a flow of gas from the termini of the cells later to receive cooling water successively and in series into the cells earlier to receive cooling water.

7. In a single pass surface condenser, means providing a plurality of cells having a vapor flow therethrough in parallel and a water flow therethrough in series, and means for directing a flow of gas from the termini of said cells in series through the cells in a direction counter to the water flow therethrough.

8. In a single pass surface condenser, means providing a plurality of cells having a vapor flow therethrough in parallel and a water flow therethrough in series, and means for directing a flow of gas from the termini of said cells in series through the cells in a direction counter to the water flow therethrough, said cells so receiving gas from another cell having means therein insuring the cooling of such gases.

9. In a condenser having a plurality of cells providing a vapor flow therethrough in parallel, means providing a water flow through said cells in series, said cells having means providing a gas flow therethrough in series in a direction opposite to said water flow.

10. In a multicellular surface condenser constructed for a vapor flow through the cells in parallel, means providing a single-pass water flow through at least a plurality of said cells in series, at least a plurality of said cells having a gas flow therethrough in series in a direction counter to said water flow.

11. In a multicellular surface condenser, means providing a single-pass water flow through at least a plurality of said cells in series, at least a plurality of said cells having a gas flow therethrough in series in a direction counter to said water flow, said gas flow being permitted by outlet openings suc-

cessively increasing in size in the direction of gas flow.

12. In a multicellular surface condenser, means providing a single-pass water flow through at least a plurality of said cells in series, at least a plurality of said cells having a gas flow therethrough in series in a direction counter to said water flow, said gas flow being permitted by outlet openings successively increasing in size in the direction of gas flow and in proportion to the condensing capacity of the cells from which they discharge.

13. In a multicellular surface condenser, means providing a single-pass water flow through at least a plurality of said cells in series, at least a plurality of said cells having a gas flow therethrough in series in a direction counter to said water flow, said gas flow being permitted by outlet openings of such size there will be a pressure drop of a few hundredths of an inch of mercury through them when passing triple the normal gas and accompanying vapor.

14. In a condenser, water tubes forming a single pass therethrough, and a partition dividing said condenser into a plurality of cells receiving vapor therein in parallel, said partition having an opening therethrough permitting a gas flow from cell to cell.

15. In a condenser, water tubes forming a single pass therethrough, and a partition dividing said condenser into a plurality of cells receiving vapor therein in parallel, said partition having an opening therethrough permitting a gas flow from cell to cell in opposition to the water flow.

16. In a condenser, water tubes forming a single pass therethrough, and partitions dividing said condenser into a plurality of cells, each of said partitions having an opening therethrough permitting a gas flow from cell to cell, said openings being of successively greater capacity in the direction of gas flow.

17. In a condenser having a main gas off-take, water tubes forming a single pass therethrough, a partition dividing said condenser into a plurality of cells, said partition having an opening therethrough of less size than said offtake permitting a gas flow from cell to cell, and a baffle cooperating with said opening.

18. In a condenser, water tubes forming a single pass therethrough, a partition dividing said condenser into a plurality of cells, said partition having an opening therethrough permitting a gas flow from cell to cell and a baffle cooperating with said opening, said baffle having flow-deflecting means thereon.

In testimony whereof I have hereunto set my hand.

RAYMOND N. EHRHART.
